(57) **CLAIM**

The ornamental design for a toilet chair as shown and described.

DESCRIPTION

FIG. 1 is a front, left and top perspective view of a toilet chair, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 1.

FIG. 12 is a front, left and top perspective view of the toilet chair in an alternative position of use; and,

FIG. 13 is another front, left and top perspective view of the toilet chair in an another alternative position of use.

The dashed broken lines depict portions of the toilet chair that form no part of the claimed design. The dot-dash broken lines in FIGS. 1, 9, 10 and 11 depict the boundaries of the enlargements that form no part of the claimed design.

1 Claim, 13 Drawing Sheets
